UNITED STATES PATENT OFFICE.

CHARLES E. DAVIS, OF CHICAGO, ILLINOIS, ASSIGNOR TO GOODMAN MANUFACTURING COMPANY, OF CHICAGO, ILLINOIS, A CORPORATION OF ILLINOIS.

DRIVING-CHAIN FOR MINING-MACHINES.

1,308,843.

Specification of Letters Patent. Patented July 8, 1919.

Application filed May 10, 1915. Serial No. 26,991.

To all whom it may concern:

Be it known that I, CHARLES E. DAVIS, a citizen of the United States, residing at Chicago, in the county of Cook and State of Illinois, have invented a certain new and useful Improvement in Driving-Chains for Mining-Machines, of which the following is a specification.

My invention relates to improvements in cutter chains for mining machines, and has for its object to provide a new and improved chain of this description.

The invention is illustrated in the accompanying drawings, wherein—

15 Figure 1 is a plan view;

Fig. 2 is a longitudinal sectional view through one of the blocks;

Fig. 3 is a cross sectional view through one of the joints where the knife carrying blocks 20 of the chain are connected together and showing the chain in the guide;

Fig. 4 is an enlarged view of the eccentric pins used in connecting the blocks together;

25 Fig. 5 is an enlarged view of the eccentric head for this pin;

Fig. 6 is an enlarged view of the bushing fitting in the end of the block and through which the pin shown in Fig. 4 30 passes;

Fig. 7 is an enlarged view of the casing or lining for the opening in the block into which the knife or cutter is received.

Like numerals refer to like parts throughout the several figures.

In the present construction I have shown a mining machine chain made up of a series of blocks 1, which carry knives or cutters 2, the blocks being directly connected together 40 without intervening links. Each block is bifurcated at one end, having two separated branches 3. At the other end of each block is a single piece 4, which is received between the branches 3 of the adjacent block.

45 Part 4 is provided with an opening into which is received a removable bushing 5 made of hardened steel, some means being provided for preventing the bushing from turning in the block. These bushings are 50 preferably made of flat pieces of steel which are formed into proper shape and the two meeting ends 6 are bent so as to project laterally, said meeting ends fitting into a groove 7 in the block and preventing the 55 bushing from turning in the block. When

constructed in this manner, the bushings are spring bushings and when placed in position spring outwardly so as to engage the inner face of the opening in the block, the bushings being thus held in place without the aid of any holding device, before the blocks are assembled. The branches 3 are provided with holes which are in alinement with the hole in the part 4 of the adjacent part so that when the part 4 is inserted between the branches 3 the connecting pin 8 of hardened steel may be inserted so as to hold the blocks together. These pins pass through the hardened steel bushings 5 and rotate therein. Some means is provided for preventing them from rotating in the openings in the branches 3 so as to confine the wear of the chain to the hardened steel bushings 5 and the hardened steel pins 8. As herein shown, this is accomplished by providing the pins 8 with enlarged eccentric heads 9 which fit into eccentric holes or countersunk openings 10 in one of the branches 3. Some suitable means is provided for holding these pins in place. In view of the fact that the pins are of hardened steel they cannot be riveted, and hence I have shown said pins as being provided with a removable eccentric head 11, which fits into an eccentric opening 12 in one of the branches 3 of the block. The pin and removable head have openings passing therethrough for a pin or rivet 13 of softer metal, which can have its ends riveted as illustrated in Fig. 3 to hold them together and thus keep the wearing pin in position. It will therefore be seen that by means of this construction the blocks containing the knives or cutters are directly connected together; and it will further be seen that the wear on these blocks comes not upon the material of the blocks themselves but upon the hardened removable bushings and pins which are able to stand the wear and which, if worn, can be easily, quickly and cheaply replaced, thereby preserving the expensive knife holding blocks and insuring the long life of the chain. By doing away with the links connecting the blocks, the number of knives for a chain of any given length is greatly increased, and this greatly reduces the wear on the chain and increases its life, and the wear on the knives is also reduced.

The chain made up of these blocks and knives passes around the usual cutter arm

14 (see Fig. 3). In Fig. 3 I have also shown the blocks as provided at the top and bottom with the projecting lips 15 at the inner edges thereof, both top and bottom, 5 which work in grooves 16 in the guiding part of the cutter arm. In Fig. 1 I have shown a construction in which these lips are omitted. The knives or cutters 3 are provided with shanks 17, which may be of 10 and desired shape but are usually rectangular. These shanks fit into openings in the blocks and are held in place in any desired manner, as by set screws 18. The blocks 1 are cast, and it has been found in 15 practice difficult to secure an opening for the shank of the knife which should be of the proper size and shape. It has been found that the sand forming the core burns away and the hole is too small and the metal has 20 to be cut out. This is expensive and makes it difficult to get a correct fit of the shank in the opening. If the hole is too small the shank cannot be placed in it, and if too large it works loose and comes out. In the 25 present construction this difficulty is obviated by providing a casing 19, of metal, such as sheet steel, the opening of which is just the size of the shank of the knife. This rectangular casing is placed around the core 30 of the mold in which the block is molded, and when the hot metal is poured into the mold it comes into contact with this metal casing and melts it sufficiently to adhere to it. Then when the core of sand is removed 35 from the casing this casing forms the inner lining for the opening for the shank. This gives a smooth inner surface to this opening and provides an opening of exactly the right size at all times, and does away with 40 the necessity of doing any machine work on it. The casing is shown separate from the block in Fig. 7 and is shown in the block in Figs. 1 and 2.

I have described in detail a particular 45 construction embodying the invention, but it is of course evident that the parts may be varied in many particulars without departing from the spirit of my invention, and I therefore do not limit myself to the particular construction shown.

As shown in Figs. 1 and 2, the space between the branches 3 of the bifurcated end of the block 1 is greater than is necessary for the projecting end of the adjacent block, 55 thereby leaving an opening 20 which extends entirely through the block. The teeth 21 of the sprocket wheel 22, at the point where the chain changes direction (see Fig. 1) project into these openings 20, and it will 60 be noted that since the openings pass entirely through the chain when it is assembled, there is no chance for these openings to become filled with foreign matter so as to interfere with the proper operation of 65 the sprocket wheel as the teeth of the

sprocket wheel will push any such foreign matter out through the end of the opening opposite them, into which the tooth enters. The sprocket wheel drives the chain when the machine is in operation, and when driving 70 it in one direction the teeth of the sprocket wheel engage the ends 23 of the blocks which project between the members 3. When the sprocket wheel moves the chain in the other direction the teeth engage 75 the walls 24 at the end of the bifurcation, and these walls must be of sufficient strength to withstand the pressure necessary to drive the chain.

In order to secure the proper thickness of 80 the metal without, on the one hand making the block unduly long or on the other hand filling up the opening in which the teeth of the sprocket wheel project, the openings in which the knives 2 fit are provided with 85 shoulders 25, these shoulders limiting the inward movement of the knives. The casing 19 is also provided with a shoulder 26 which fits the shoulder 25.

I claim:

1. A chain for mining machines formed of 90 links perforated near their opposite ends, pins for uniting the links, and bushings with which the said pins engage seated in the perforations in one of the end portions of the 95 links, the bushings being each formed of a piece of metal bent into cylindrical shape, the ends of the metal of the bushing being bent outwardly and brought close together and substantially parallel, the said ends being 100 fitted into a groove formed in the link and communicating with the perforation in which the bushing is seated.

2. A block for cutter chains for mining 105 machines, comprising a body portion having openings therethrough at opposite ends thereof, a removable bushing in the opening at one end of the body portion and provided with a projecting part which fits into a groove in the body portion, a pin passing 110 through the opening at the other end of said body portion, said pin provided with an eccentric head, the opening at the said other end being enlarged to receive said eccentric head, and means for fastening said pin in 115 position.

3. A block for cutter chains for mining 120 machines, comprising a body portion having openings therethrough at opposite ends thereof, a removable bushing in the opening 125 at one end of the body portion, means for preventing said bushing from rotating with relation to said body portion, a member provided with an eccentric head, and with a projecting part which projects into the opening at the other end of said block, said opening being enlarged to receive said eccentric head, and means for holding said member in position.

4. A block constituting one of the ele- 130

ments of a chain for mining machines having one of its ends formed into separated branches and its opposite end shaped to fit between the branches of a similar block, the block being perforated near its opposite ends to receive the connecting parts that unite it with similar blocks, and one of the branches having formed in its outer face an eccentric recess, in combination with a pin adapted to pass through registering perforations of blocks that are to be united, the pin having at one of its ends an eccentric head adapted to fit said recess in the block and hold the pin against relative rotation, a separate head for the opposite end of the pin, and means for uniting the separate head to the pin.

5. A block constituting one of the elements of a chain for mining machines having one of its ends formed into separated branches and its opposite end shaped to fit between the branches of a similar block, the block being perforated near its opposite ends to receive the connecting parts that unite it with similar blocks, and the branches having formed in their outer faces eccentric recesses, in combination with a pin of hardened metal serving as a pintle for connecting blocks having an eccentric head adapted to fit into one of the said eccentric recesses, a

separable head for the pin adapted to fit into 30 the other eccentric recess and a rivet of softer metal passing through the pin and uniting its separate head thereto and thus securing it in working position.

6. A block for cutter chains for mining 35 machines, comprising a body portion having an opening therethrough at one end, a sleeve of hardened metal passing through said opening, means for preventing said sleeve from rotating with relation to said body portion, 40 the other end of said body portion having two separated branches adapted to receive between them the adjacent part to which said block is connected, each of said branches having an opening, a pin of hardened metal 45 passing through said openings, an enlarged eccentric head connected with said pin, one end of the opening in the body portion being enlarged to receive said eccentric head, and means for fastening said pin and head to 50 said body portion.

In testimony whereof I affix my signature, in the presence of two witnesses, this 22nd day of April, 1915.

CHARLES E. DAVIS.
